THREAD CUTTER

Joseph Chudner, Brooklyn, N. Y.

Application June 13, 1944, Serial No. 540,127

8 Claims. (Cl. 112—252)

This invention relates to a thread cutting mechanism which may be incorporated advantageously in a sewing machine.

An object of the invention is the provision of a cutting mechanism of the indicated character for cutting both the over thread from the spool and the under thread from the bobbin.

A further object is the provision of a mechanism as characterized above not only capable of cutting two threads, but capable of cutting the threads at points close to the sewing or stitching, or if desired, beyond the same, to leave end portions of the threads on the work, and in either case the threads held for continuing anew the stitching or sewing operation.

A further object is the provision of a thread cutter for a sewing machine which releases the thread tensioning means of the machine prior to cutting the top thread to the needle so as to assure continual sewing.

With the foregoing, other objects and benefits of the invention will appear when the following specification is read in connection with the accompanying drawings in which—

Fig. 1 is a side elevational view of a sewing machine selected by way of example to illustrate the thread cutting mechanism of the present invention applied thereto.

Fig. 2 is a top plan view partly in section indicated by the line 2—2 of Fig. 1.

Fig. 3 is a view of a detail of the top thread tension release.

Fig. 4 is an enlarged end view of the needle bar and presser foot assembly.

Fig. 5 is an enlarged perspective view of parts of the top thread cutter applied to the presser foot, the latter being raised.

Fig. 6 is a view partly in section and partly in plan of the top thread cutter applied to the presser foot, the movable cutting member being shown in its normal position, the section being taken on the line 6—6 of Fig. 5.

Fig. 7 is a view similar to Fig. 6, but showing the aforesaid cutting member in its retracted position.

Fig. 8 is an enlarged sectional view taken on the line 8—8 of Fig. 6.

Fig. 9 is a fragmentary longitudinal sectional view of the mechanism with parts in the relation they assume during the stitching or sewing operation.

Fig. 10 is a sectional view of parts shown in Fig. 9 on an enlarged scale.

Fig. 11 is an enlarged sectional view showing

cutting members in action cutting the top and bottom threads.

Fig. 12 is a top plan view of the under part of the cloth plate together with parts of the bottom thread cutter.

Fig. 13 is a longitudinal sectional view of parts of the bottom or under thread cutter in action pinching or gripping the thread while cutting it.

The thread cutting mechanism of the present invention, as applied to a conventional sewing machine involves parts of the machine as follows: bed 10, arm 11, cloth-plate 12, presser foot 13, needle 14, needle-bar 15, automatic top thread tension 16, and presser foot lifter 17.

15 The top or over thread from the spool carried by the pin on the arm 11 is cut by means which operates in conjunction with the presser foot 13. The presser foot is recessed, as at 18, and has a sole plate 19 removably secured to close the recess at the bottom and to provide a cutting member having a cutting edge 20. A movable cutting member 21 is mounted on the presser foot in the recess 18 for pivotal or oscillatory movement with respect to the cutting member 19. Ac-

20 cordingly, as shown in Figs. 5-9, a pivot 22 on the cutting member 21 is turnably supported by the heel of the presser foot. The cutting member 21 is substantially crescent shape to provide a front curved edge 23 and a rear curved cam surface 24.

25 The cutting member 21 is undercut to provide a cutting edge 25 below and behind the edge 23. An arm 26 extends radially from the upper end of the pivot 22 and said arm 26 has a ball 27 on its outer end.

30 It is to be understood the cutting member 21 moves up and down with the presser foot 13 and also pivots with respect thereto. The cutting member 21 is only operated when the presser foot 13 is in the down position. Normally, the cutting member 21 is in the cutting position when the machine is sewing.

35 The top thread 28 from the spool 29 passes through the eye of the needle 14 and extends downwardly between the toes of the presser foot behind the cam surface 24 of the cutting member 21. As the cutting member 21 pivots to the retracted position the thread 28 is flexed by the camming action of the surface 24, so that the cutting member 21 clears the thread 28, which is then disposed downwardly in advance of the front edge 23.

40 As the cutting member 21 pivots from the retracted position it carries the thread 28 into the recess 18, thereby releasably pinching the thread 28 between the presser foot and the cutting member 21 and at the same time 45 the edge 25 coacts with the edge 20 in a shearing

50 55

action cutting the thread 28 at a point beyond the needle with the thread still passing through the eye of the needle. The thread 28 is therefore severed close to the stitching or sewing and after the cutting operation the sewing may be continued anew without any subsequent manipulations.

In order to operate the cutting member 21 for the stated purposes, there is provided means presently to be described. A lever 30 is fulcrumed, as at 31, on the presser foot 13. The lower end of the lever 30 has a slot 32 which receives the ball 27 of the arm 26 so that upon oscillation of the lever 30, the arm 26 will be oscillated in turn, thereby causing the operation of the cutting member 21. The upper end of the lever 30 carries a stud or pin 33. An arm 34 is fixedly clamped, as at 35, on the forward end of reciprocal rod 36. The arm 34 depends from the rod 36 and its lower end has a slot 37 which receives the pin 33. Upon forward movement of the rod 36, the arm 34 through the intervention of the pin and slot connection 33-37 moves the lever 30 in one direction to retract the cutting member 21. The aforesaid pin and slot connection enables raising of the presser foot 13 without upsetting the operative relationship of the counterparts. The rod 36 is supported for reciprocal movement by bearing brackets 38 and 39, respectively, on the arm 11. A cushion coil spring 40 surrounds the rod 36 and has one end bearing against a head 41 on the rod 36 and its other bearing against the bracket 39. A yoke lever 42 straddles the arm 11, and is fulcrumed thereon, as at 43. The head 41 of the rod 36 is connected with the lever 42 by a pin and slot connection 44-45. The fulcrum 43 extends transversely through the arm 11 and has a radially disposed rod 46 extending downwardly through the bed 10. A retractile coil spring 47 has one end connected with the rod 46, as at 48, and its opposite end connected, as at 49, with a fixed stud 50 on the underside of the bed 10. The control lever 42 has limited movement in opposite directions by stops 51 and 52, respectively, on the arm 11. The lever 42 is normally in engagement with the stop 51 under the action of the springs 40 and 47 with the cutting member 21 in the cutting position.

In order to prevent the mechanism from being operated when the presser foot is raised, means is provided which cooperates with the presser foot lifter 17. Said means consists of a shoulder or the like 53, in the present instance formed on the rod 36 by reason of a notch in the rod, as shown most clearly in Fig. 5. When the lifter 17 is up for the purpose of holding the presser foot in the raised position, the shoulder 53 will encounter the lifter 17 and so prevent movement of the rod 36 and parts connected therewith.

In order to release the tension of the thread 28 when the presser foot 13 is down and at the time the thread is being pinched by the cutting member 21 just prior to the thread being cut, means is provided which operates in conjunction with the thread tension 16. Said means in the present instance consists of a cam surface 54 on the rod 36, as shown in Figs. 3 and 5. The cam surface 54 coacts with a rod 55 incorporated in the tension 16 in such manner that, as the rod 36 moves to cause the actuation of the cutter member 21, the tension 16 will be operated to release the thread. Thus, it will be possible for the cutting member 21 to pull the thread 28 into the recess 18 to pinch it against the pressure foot 13, sub-

ject to the withdrawal of the thread upon the movement of the needle 14. Upon the return movement of the rod 36 to its normal position, the thread 28 will be automatically placed under tension again.

In order to cut or sever the under or bottom thread 60 from the bobbin simultaneously with the cutting of the top thread 28, there are provided means, presently to be described, housed 10 and operatively arranged on the bed 10 and cloth or throat plate 12. This plate 12 is of two parts, there being an upper part 61 and lower and smaller part 62 held together by screws 63 on the bed 10. The parts 61 and 62 have aligned holes 64 and 65, respectively, which receive the needle 14 and threads 28 and 60 in the usual operation of the machine. The part 61 is undercut to provide an inclined surface 66 at the hole 64 whose circular wall embodied by the part 61 provides a cutting edge 67. The part 62 has elongated guide grooves or recesses 68 and 69, respectively in the upper and lower surfaces shown most clearly in Figs. 12 and 13. An elongated steel cutting member 70 is arranged for sliding movement in the recess 68. The member 70 has an upturned transverse cutting edge 71 on the springy forward end, and also has a longitudinal slot 72 to accommodate the feed surface 73. There is also a slot 74 in the rear end of the member 70 to provide abutments 75 and 76 respectively. A motion transmission member and thread puller 77 consisting of an elongated piece of metal is arranged for sliding movement in the recess 69. This part 77 has a longitudinal slot 78 which accommodates the feed surface 73. An upstanding lug 79 on the part 77 is received in the slot 74 to cooperate with the abutments 75 and 76. The rear end of the part 79 has a notch 80 therein. The part 77 rests on the bed 10 40 which, together with the plate 12, form a guide for the part 77. A bell-crank lever 81 is mounted on the plate 12 and has one end engaged in the notch 80 and its other end is pivotally connected, as at 82, with one end of a rod 83 whose opposite 45 end has a slot which receives the lower end of a throw member 84, as at 85. The throw member 84 is adjustably secured to the lever 42, with respect to the fulcrum 43, by screws 86 and slots 87, respectively, the screw 86 being on the lever 42 and the slots 87 being in the throw member 84. The member 84 and lever 42 move in unison and cause the operation of the bell-crank lever 81.

It will now be understood that when the lever 42 is pushed forwardly through the intervention 55 of the member 84 and lever 81, the part 77 will be slid forwardly from its normal position in which the lug 79 is back away from the abutment 75 in contact with the abutment 76. The forward movement of the part 77 causes the front end to pull the thread 60 from the bobbin to afford a certain amount of slack. As the part 77 continues to be moved forwardly the lug 79 encounters the abutment 75 causing the cutting member 70 to slide forwardly with the part 77. This will cause the cutting edge 71 to cooperate with the cutting edge 67 to thereby cut or sever the thread 60, and at the same time cause the member 70 to pinch the thread 60 against the part 62 of the plate 12. When the lever 42 is 60 released, it will be returned by the springs 40 and 47 against the stop 51, after causing the reverse movement of the part 77 and the cutting member 70 in which the lug 79 encounters the abutment 76. The lost motion afforded by the slot 74 and lug 79 enables sufficient thread to be

pulled from the bobbin to assure continuance of the sewing anew.

It is therefore understood that the over thread 28 and the under thread 60 may be cut simultaneously close to the sewing or stitching; that sufficient end portions of the threads remain for continuing the sewing anew; and that the presser foot may be raised and the threads pulled by hand to leave long ends on the work before cutting the threads subject to the lowering of the presser foot; that the needle must be raised prior to the thread cutting operation; and that the mechanism can not be operated while the presser foot is raised and thereby averting damage to parts of the mechanism.

I claim:

1. In a thread cutting mechanism for a sewing machine, the combination of a presser foot, thread cutting means operatively mounted on said presser foot, means including a reciprocal rod for operating the cutting means, a presser foot lifter, and means on said rod which cooperates with said lifter when the latter is in the up position to prevent the cutting means from being operated while the presser foot is raised.

2. In a thread cutting mechanism for a sewing machine, the combination of thread tensioning means, thread cutting means, means to operate the cutting means including a reciprocal rod having a cam surface, and means operated by the cam surface to operate the tensioning means to release the tension on the thread prior to thread cutting action.

3. In a thread cutting mechanism for a sewing machine, cooperative cutting members one of which is fixed and the other one being slidably, a thread pulling member mounted to slide with respect to said slidable cutting member, coacting means on the slidable cutting member and the thread pulling member whereby said thread pulling member may be caused to slide for a part of its travel with respect to the cutting member and then cause the cutting member to slide with the thread pulling member to perform the following functions, namely, to pull the thread to provide a take-up portion, then pinch said portion, and then sever the thread beyond the point where it is pinched, and means to slide said thread pulling member in opposite directions.

4. A thread cutting mechanism for a sewing machine comprising cooperative cutting members one of which is movable and the other being fixed, and means to operate the movable cutting member, said means including a manually operable rocker on the arm of the machine, a slidable rod on said arm, levers on the presser foot of the machine, one of said levers being connected with the movable cutting member, the levers being cooperatively engaged, an arm on one end of said

rod, a pin and slot connection between said arm and the other of said levers, and said rocker being pivotally connected with the other end of said rod, and a retractile spring acting on said rocker.

5. In a thread cutting mechanism for a sewing machine, the combination of a presser foot, cooperative cutting members on said presser foot, one of said cutting members being fixed and the other cutting member being movable, a control lever, and means to transmit motion from the control lever to the movable cutting member to operate it, said movable cutting member normally disposed in the cutting position at one side of the thread to be cut, and said movable cutting member being so constructed and shaped that it flexes the thread while moving from the cutting position to its retracted position and then carries the thread toward the fixed cutting member to be cut by the cooperative action of the cutting members as the movable cutting member moves into the cutting position.

6. In a thread cutting mechanism for a sewing machine, the combination of a presser foot, cooperative cutting members on said presser foot, one of said cutting members being fixed and the other cutting member being movable, a control lever, and means to transmit motion from the control lever to the movable cutting member to operate it, said movable cutting member substantially crescent shape and normally disposed at one side of the thread to be cut so that it flexes the thread while moving from the cutting position to its retracted position and then carries the thread toward the fixed cutting member to be cut by the cooperative action of the cutting members as the movable cutting member moves into the cutting position.

7. In a thread cutting mechanism for a sewing machine, the combination of a presser foot, cooperative cutting members on said presser foot, one of said cutting members being fixed and the other cutting member being movable, a control lever, means to transmit motion from the control lever to the movable cutting member to operate it, and a presser foot lifter which cooperates with said last means when said lifter is in the up position to prevent the movement of said control lever.

8. In a thread cutting mechanism as set forth in claim 3, wherein the slidable cutting member consists of an elongated blade with a cutting edge on one end, and said coacting means consists of spaced abutments on the slidable cutting member, and a lug on the thread pulling member disposed for movement between said abutments into and out of engagement therewith in response to the movement of the thread pulling member.

JOSEPH CHUDNER.
